BALL RETURN AND PROJECTING MECHANISM FOR AMUSEMENT GAME APPARATUSES

Harry E. Williams, Chicago, Ill., assignor to Williams Patent Corporation, a corporation of Illinois

Application June 24, 1946, Serial No. 678,841

3 Claims. (Cl. 273—121)

1

This invention relates to certain new and useful improvements in ball return and projecting mechanism for amusement game apparatuses of the type known as a bagatelle game in which balls are successively propelled or projected to an upper end portion of an inclined playing board for gravitation theredown into and against targets or other baffles to a position in what is known as an out ball return pocket.

The present invention is more particularly concerned with mechanism for delivering the balls from the return pocket to an arcuate runway from whence the balls are deposited in a projection alley along which they are projected by a ball projecting means. In this aspect of the invention an object is to provide a mechanism for controlling the movement of the balls from the ball return pocket to a position in front of a ball projector, with the balls visible at all times to the player.

Another object of the invention is to provide such a mechanism which will be simple in construction, easy of operation, and economical in manufacture, a mechanism which is positive and accurate in its operation, and one which will not easily become defective by continuous and rough usage.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary top plan view of a game apparatus in which my invention is associated;

Fig. 2 is a fragmentary plan view of the playing board embodied in the game apparatus shown in Fig. 1, viewing the same from the bottom thereof;

Fig. 3 is a perspective view of the mechanism shown in the left-hand portion of Fig. 2, as viewed at a perspective angle from the bottom of the playing board;

Fig. 4 is a perspective view of a mounting plate embodied in the invention;

Fig. 5 is a perspective view of the mechanism shown in the right-hand portion of Fig. 2, as viewed from the bottom of the playing board;

Fig. 6 is a perspective view similar to Fig. 5 but showing the parts thereof in a different position;

Fig. 7 is a fragmentary perspective view of the underside of the playing board showing part of the ball dislodging mechanism;

2

Fig. 8 is a fragmentary sectional detail view of the same taken on line 8—8 of Fig. 2.

The several objects of my invention are accomplished by the preferred form of construction illustrated in the drawings. In this connection the amusement game apparatus having incorporated therein my invention is indicated at 10 and includes a cabinet 11 having a playboard 12 over which balls are adapted to gravitate from the upper end portion thereof to a lower end portion for contact with targets or other baffle means (not shown). Over this playboard 12 is usually disposed a glass top (not shown).

At the lower end portion of this playboard 12 and within the cabinet 11 is a block 13 having converging edge portions 14 against which the balls are adapted to contact and be guided to an outlet 15 into a ball pocket 16 formed diagonally of the board 12. Below this pocket 16 the block 13 provides a ball runway 17 into which balls from the pocket 16 are delivered for movement to the lower end portion 18 of the runway 17 from whence the balls are propelled through a return trough 19 to a position in front of a projector 20, which projector 20, when operated, projects the ball up a runway 21 to the upper end portion of the board 12 from whence it gravitates, as before stated. This projector 20 may be of any approved construction now commercially in use and including a plunger rod 22 urged into ball projecting position by means of a spring 23. This projector does not per se comprise the present invention.

Associated with the cabinet 11 is a coin slide 24 including a slide member 25. This coin slide is constructed in accordance with the disclosure of United States Patent No. 1,908,380, dated May 9, 1933, granted to one Tratsch on a Coin Slide. The slide member 25 is hand-operated and the inner end portion 26 thereof projects into the cabinet 11 beneath the board 12 for reasons hereinafter set forth.

The pocket 16 is formed by a cut-out 27 provided in the board 12 with a mounting plate 28 (Fig. 4) normally closing this cut-out 27 and constituting the bottom wall of the pocket 16. This plate 28 is secured to the underside 29 of the board 12 by means of connecting screws 30 (Fig. 2). At each end of the plate 28 are formed elongated slots 31. At each end of the plate 28 there are provided upstanding lugs 32 perforated as at 33 (Fig. 4).

Pivotedly connected to these lugs 32 by means of pins 34 (Fig. 7) is an actuated bar 35 providing angled portions 36 to which the pins 34 are

connected in any suitable manner, such as by spot welding or the like. This actuated bar 35 has secured thereto as at 37, by spot welding or the like, oppositely disposed plates 38 which are adapted, when the actuated bar 35 is pivoted relative to the lugs 32, to pass into the slots 31 of the plate 28 (Fig. 7). Disposed on the top surface of the plate 28 (Figs. 1 and 8) is an elongated ball lift bar 39 having angled end portions 40 secured to the plates 38 as at 41 by means of threaded bolts or the like.

In the board 12 at the lower right-hand corner as viewed in Fig. 1, there is provided a cut-out 42 (Fig. 7) which communicates with the lower end portion of the runway 17 beneath the block 13.

A blocking arm is indicated at 43, and this arm is adapted to block the operation of a ball transfer mechanism (hereinafter described) when the actuated bar 35 is pivoted to move the lift bar 39 from the pocket 16 to the dotted line position as shown in Fig. 8, for reasons herein-after set forth. This blocking arm is fixed to a pivot bar 44 as at 45. This pivot bar 44 is pivotally connected to a supporting lug 46 as at 47, the supporting lug 46 being connected as at 48 to the underside of the board 12. The end portion 49 of this pivot bar 44 is disposed in the path of a lateral projection 50 formed on the actuated bar 35, the arrangement being such that when the actuated bar 35 is pivoted in an anticlockwise direction as viewed in Fig. 7, the bar 44 will pivot in an anticlockwise direction as viewed in Fig. 7, under the action of a spring 51, to dispose the blocking arm 43 in the path of the ball transfer mechanism, hereinafter described.

The means for actuating the bar 35 to move the ball lift bar 39 is illustrated in the perspective view shown in Fig. 3, a plan view being shown in the left-hand portion of Fig. 2. This mechanism includes an elongated plate 53 mounted for slidable movement relative to mounting brackets 54 secured as at 55 by means of screws to the underside of the playing board 12. Adjustably secured to this plate 53 by means of bolt and slot connections 56 is an abutment plate 57 disposed in the path of movement of the slide member 26 and moved by the slide member 26 against the action of a spring 58 connected as at 59 to the plate 57 and to the underside of the board as at 60. Secured to this plate 53 by a transverse arm 61 and extending parallel therewith is an operating bar 62 having a cam surface 63 which is adapted to engage the end portion 64 of the actuated bar 35 whereby when the plate 53 and bar 62 are moved in the direction of the arrow (Fig. 3), the cam 63 will engage the end portion 64 of the bar 35 and pivot the same in an anticlockwise direction as viewed in Fig. 7, against the action of a spring 65, one end of which is connected as at 66 to the bar 35 and the opposite end as at 67 to the playing board 12.

The operation of the structure thus far described is as follows:

As the balls reach the lower end portion of the playing board 12 they will roll by gravity into the pocket 16. At the completion of a game and at the start of a new game, when the coin slide 25 is moved inwardly, the end 26 thereof will engage the plate 57 and impart sliding movement to the plate 53 and bar 62 in the direction of the arrow (Fig. 3), against action of the spring 58. As the high part of the cam surface 63 bears against the end portion 64 of the actuated bar 35, the bar 35 will be pivoted in an anticlockwise direction as viewed in Fig. 7. This pivotal move-

ment of this bar 35 will pivot the ball lift bar 39 in an anticlockwise direction as viewed in Fig. 8, and the balls resting thereon will be projected from the pocket 16 into the runway 17 over a guide strip 67 secured in any suitable manner to the floor of the runway 17 as at 68. When the balls are received by this runway 17, they will gravitate to the lower end thereof in a position to be transferred through the return runway to ball projecting position in the runway 21.

This transfer of the balls in successive order from the lower end portion 18 of the runway 17 to ball projecting position in the runway 21 forwardly of the plunger rod 22, is accomplished by the mechanism illustrated in the right-hand portion of Fig. 2 and in Figs. 5 and 6. This mechanism will now be described.

A ball transfer arm is indicated at 69 and includes a head 70 which is adapted to engage the balls. This arm 69 operates within the cut-out 42 and through the runway 19. The arm 69 is secured as at 71 to a plate 72 by means of spot welding or the like. This plate 72 is pivotally connected to the board 12 by means of a pintle structure 73 including a spacer sleeve 74 which spaces plate 72 from the head 75 of the pintle structure. This plate 72 is connected at its outer end portion by means of a spring 76 to an arm 77. One end portion 78 of this arm 77 has a strike plate 79 which is adapted to be engaged by the end 80 of a plunger 81 of a well known construction and having an operating head 82 thereof disposed exterior of the cabinet 11. This plunger is of a well known construction and per se does not constitute the invention and is schematically shown in Figs. 5 and 6. This arm 77 is pivotally connected as at 83 to the plate 28 (Fig. 5). There is adjustably connected to this arm 77 by means of a bolt and slot connection 84, a trip arm 85. This trip arm 85 is adapted to engage a pin 86 carried by the arm 87 of a bell crank 88 pivotally connected at 90 to a mounting plate 89 secured to the underside of the playing board 12 as at 91. The arm 92 of this bell crank provides a latch head 93 which is adapted to have latched engagement with a finger 94 carried by the plate 72, the plate 72 through its finger 94 being connected by means of the spring 76 to the arm 77. A depending lug 95 extends from the plate 72 in the path of movement of the arm 77, to limit the relative movement in an anticlockwise direction, as viewed in Fig. 5, of this arm 77 under the action of a spring 96, one end of which is connected as at 97 to the lug 46 secured as at 48 to the underside of the board 12 and the opposite end as at 100 to the arm 77. The bell crank lever 88 is normally pivoted in a clockwise direction to dispose the latch head 93 in latched engagement with the finger 94 of the plate 72. The operation of the foregoing structure is as follows.

When the plunger head 82 has the pressure of the thumb of the operator applied thereto, the plunger will be moved in a direction to bear the end 80 against the strike plate 79. Continued movement of this plunger 81 with its end 80 in engagement with the strike plate 79 will pivot the arm 77 against the action of the spring 96 to move the trip arm 85 into tripping engagement with respect to the pin 86, whereupon continued movement of the arm 77 with the trip arm 85 bearing against the pin 86, will pivot the bell crank arm 92 against the action of the spring 103 to move the latch head 93 from latched engagement with the finger 94 of the plate 72. As the spring 16 has been placed under tension

by the foregoing operation, including movement of the arm 71 in a clockwise direction, as viewed in Fig. 5, the release of the latch head 93 from the latch arm 72, will cause this arm 72 to pivot with spring action so as to move the transfer arm 69 into contact with the ball B in the runway 17, and move this ball B with snap action through the return runway 19 to a position forwardly of the plunger 22.

Upon release of the plunger head 82 by the player, the spring 96 will return the arm 71 to its normal position shown in Fig. 5, and in that return the plate 72 will be returned to its normal position by the spring 76, as will the bell crank arm 92 by its spring 103, ready for the next operation of transferring a ball from the lower end portion of the runway 17 through the return runway 19 into the projection runway 21.

By this simple operation, it is obvious that a minimum effort upon the part of the player is required to transfer a ball from the runway 17 to the projection runway 21 and that this transfer of the ball becomes automatic as soon as the plunger 81 has moved the arm 71 a predetermined distance to release the latch head 93 of the bellcrank arm 92 from latched engagement with the plate 72. By this arrangement, the only control which a player has over the transfer of the ball is through the plunger 81, which, after it has been moved a predetermined distance in the direction of its length, automatically sets the transfer mechanism into operation for transferring the ball in the manner hereinbefore stated. This eliminates the delay in the operation of the game due to an involved transfer of the ball from one position to another.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. An amusement game apparatus including an inclined board having at one end thereof a ball pocket and over which board balls are adapted to gravitate into said ball pocket, said board having at one side edge thereof a projection runway communicating with the top of the board for delivering balls to the top portion of the board for gravitation thereover, said board also having adjacent and parallel to said ball pocket a ball runway, a return runway opening communication between the ball runway and the ball projection runway, means for transferring balls from said ball pocket to the ball runway, means for transferring said balls from said ball runway through said return runway to the ball projection runway, means for projecting the balls through said projection runway to the upper end of the board, said means for transferring the balls from the ball pocket to the ball runway comprising a ball lift member extending longitudinally within said ball pocket, means for supporting said lift member for pivotal movement in a direction to transfer the balls from the ball pocket to the ball runway, means for pivotally

moving said ball lift member, and means adapted to block operation of the ball transfer means when said ball lift member is operated to transfer balls from the ball pocket to the ball runway.

5 2. A game apparatus including an inclined board having a ball projection runway at one side thereof and communicating with the upper end of the board for delivering a ball to said upper end for gravitation over the board, said board having a ball trap at the lower end portion thereof, a ball receiving runway adjacent and parallel with respect to the trap and in a plane slightly thereabove, a return runway opening communication between said ball receiving runway and said projection runway, means in said trap for transferring balls therefrom into said ball receiving runway, means for transferring balls from said ball receiving runway through said return runway to said projection runway, said transferring means including a spring-actuated ball engaging member, a trigger for releasably holding said member against ball engaging movement, and manually operable means for tensioning the spring of said spring-actuated ball engaging member and for releasing said trigger to release the said tension spring.

30 3. An amusement game apparatus including an inclined board having at one end thereof a ball pocket and over which board balls are adapted to gravitate into said pocket, said board having at one side edge thereof a projecting runway communicating with the top of the board for delivering balls to the top portion of the board for gravitation thereover, said board having adjacent and parallel to said pocket a ball runway, a return runway opening communication between the ball runway and the ball projecting runway, an elongated guide strip between said pocket and said ball runway and over which balls from said 35 pocket are adapted to be lifted into said ball runway, a ball lift member pivotally supported by said board and extending longitudinally within said pocket along the bottom thereof for engaging and transferring balls over said strip from said pocket to said ball runway, means for pivotally moving said ball lift member in ball transferring direction, means for transferring said balls from said ball runway through said return runway to the ball projecting runway, and 40 means for projecting the balls through said projecting runway to the upper end of said board.

HARRY E. WILLIAMS.
